PAPER-ROLL STORAGE CONTAINER

George F. Brillante, W. Beresford Ave., De Land, Fla.

Filed Nov. 22, 1963, Ser. No. 77,542

Term of patent 14 years

(Cl. D52—2)

FIG. 1 is a front elevational view of a paper-roll storage container showing my new design;

FIG. 2 is a rear view thereof;

FIG. 3 is a side view thereof;

FIG. 4 is a top view thereof; and

FIG. 5 is a perspective view showing paper-roll insertion and removal doors in their open positions.

The side of the storage container not shown in the drawing is substantially the same as the side shown.

I claim:

The ornamental design for a paper-roll storage container, as shown and described.
